DRAIN BOARD

William D. Timmons, Coshocton, Ohio

Application February 3, 1954, Serial No. 28,820

Term of patent 14 years

(Cl. D4—2)

Fig. 1

To all whom it may concern:

Be it known that I, William D. Timmons, have invented a new, original, and ornamental Design for a Drain Board, of which the following is a specification, reference being had to the accompanying drawing, forming a part thereof.

Fig. 1 is a top perspective view of a drain board, showing my new design.

Fig. 2 is a sectional view thereof taken on lines 2—2 of Fig. 1.

I claim:

The ornamental design for a drain board, substantially as shown.
